UNITED STATES PATENT OFFICE.

CHARLES H. CHAPMAN, OF WINCHESTER, MASSACHUSETTS, ASSIGNOR TO CHAPMAN
GRAVITY SPINDLE COMPANY, OF WINCHESTER, MASSACHUSETTS, A CORPORATION
OF MAINE

SPINNING-SPINDLE.

1,075,461.

Specification of Letters Patent.

Patented Oct. 14, 1913.

Application filed January 5, 1910. Serial No. 536,565.

To all whom it may concern:

Be it known that I, CHARLES H. CHAPMAN, a citizen of the United States, residing at Winchester, in the county of Middlesex and State of Massachusetts, have invented a certain new and useful Improvement in Spinning-Spindles, of which the following is a full, clear, and exact description.

The object of this invention is to provide a bobbin-holder and a whirl-base and whirl for spinning spindles, of such character that in applying them to the spindle, and in use, the spindle will not be sprung out of equilibrium and perfect alinement.

In spinning spindles now in general use, an upwardly and outwardly flaring cup, forming a part of the whirl or whirl-base, is made to receive and hold by frictional contact the lower and externally tapered end of the bobbin; and inasmuch as the bobbins are not perfectly true, and are subject to change incident to use and barometric and thermometric variations, and it is impossible in practice to prevent them from getting out of true, it follows that when such an imperfect bobbin is forced on to the spindle, the spindle is sprung out of perfect alinement, thereby causing the spindle to take on a vibratory motion, which tends to lower the speed of the spindle and produce slack yarn, even though the bobbin is forced down and into the frictional tapered cup with sufficient force to prevent it from working loose, and when so forced onto the spindle it makes it very hard to pull the bobbin off the spindle. The cup-shaped construction tends to cramp the spindle out of perfect alinement, resulting, as before stated, in causing the spindle to take on a vibratory motion, detrimental to the life of the spindle and the quality of the yarn spun.

One important feature of the present invention consists in a hollow whirl-base, having a cylindrical extension internally counterbored so as to have only a small or short direct contact with the spindle, and a whirl fitted in said whirl-base, with a disk interposed and forcibly fitted to the spindle some distance below the plane of contact of the cylindrical extension of the whirl-base with the spindle, so that, in connection with the bobbin-holder, all possibility of the spindle

blade being sprung out of perfect alinement is overcome.

55

In the accompanying drawings, illustrating the invention, in the several figures of which like parts are similarly designated, Figure 1 is a longitudinal section, the spindle being in elevation, and the spindle and bobbin broken out. Fig. 2 is a plan view of the disk. Fig. 3 is an elevation of the bobbin-holder. Fig. 4 is a bottom plan view of the bobbin-holder.

The spindle 1, may be of any desired construction, and is adapted to fit and rotate in any of the well-known spindle supports. The bobbin 2, is constructed with an upwardly tapered hole at its upper end to fit the cylindrical portion 3 of the spindle 1, 70 with an easy slip fit, and said bobbin has no other direct contact with the spindle. The lower end of the bobbin 2 is counterbored at 4 on an arc of a circle described in a vertical plane to fit the bobbin-holder 5. One 75 form of bobbin-holder which may be used in connection with the present invention, is composed of the cylindrical portion 6, and spring portions 7, which terminate in a hollow spherical segment 8, complementary to 80 and forming a seat for the arcual portion 4 of the bobbin. The spring portions 7 are shown as four in number, although any desired number may be provided, and they are formed by slitting the body of the bobbin-holder longitudinally, as shown at 9. This segmental portion 8 of the bobbin-holder and the arcual portion 4 of the bobbin form 85 a sort of ball or universal joint for indirectly connecting the bobbin at that point 90 with the spindle. The bobbin-holder approximates a bell in shape, and the spring portions 7 partake of the curvature of the body so as to insure the necessary rigidity or resistance. The cylindrical portion 6 is 95

of sufficient length to hold the segmental portion concentric with the spindle, and its wall is thin so as to prevent any possibility of springing the spindle blade when said cylindrical portion is forced down upon the 100 spindle. The cylindrical portion is the only part of the bobbin-holder that comes into contact with the spindle.

The whirl-base 10 is hollow, and provided with a cylindrical extension 11, counterbored 105 from the bottom upwardly so as to leave

only a short contact portion 12, whereby it is forcibly fitted to the spindle, while free and clear of it for the remainder of its length. The lower end of the bobbin rests 5 upon the upper surface of the whirl-base. In the lower portion of the whirl-base is fitted a disk 13, having a central hole by which it is applied with a tight fit to the spindle, and below this disk is the whirl 14 forced 10 into the whirl-base.

It is to be noted that the bobbin-holder and whirl-base are out of contact with one another; and that the extent of contact of the whirl-base with the spindle by means 15 of its portion 12 and disk 13 is so short longitudinally, and these two planes of contact are so spaced apart, that the whirl-base and whirl are held firmly on the spindle and concentrically with it and there is overcome 20 any possibility of springing the spindle blade out of perfect alinement, thereby obviating the necessity of straightening the spindle blade after pressing on the whirl-base. With the ordinary whirl-base, the walls 25 of the shank are much thicker than the walls of the shank of my whirl-base, and they take a longitudinal bearing on the spindle blade of much greater length than mine. With a whirl-base constructed with the walls 30 of its shank thick and taking a bearing of greater length on the spindle blade, any imperfections in the hole of the shank of the whirl-base, or of that part of the spindle blade taking bearing contact in the hole 35 of the shank, tend to and will throw the spindle blade out of perfect alinement, necessitating the straightening of the spindle blade after the whirl-base is forced on to the spindle; and it is to be remembered that 40 the term "straightening," as herein applied, simply means equalizing and balancing what is and still remains an imperfect spindle blade.

The segmental seat 8 of the bobbin-holder 45 yields to the downward pressure of the bobbin and readily enters the lower end of the bobbin and springs out into contact with the walls of the arcual portion 4 thereof. The tension of the spring portions 7 is such 50 as to permit the bobbin to be readily pulled off of the spindle, and yet it is sufficient to

cause the bobbin to rotate with the spindle, while preventing it from rising from its seat by reason of any vibratory motion of the spindle. It will be readily seen that with 55 this spring bobbin-holder engaging the lower of a bobbin which has at its upper end a loose slip fit with the spindle, the upper end of the bobbin could be moved laterally in any direction, to a limited extent without 60 cramping the spindle blade, and this lateral freedom of the bobbin prevents the possibility of the spindle blade being sprung out of its perfect equilibrium.

The disk may be dispensed with and the 65 hole through the whirl-base counterbored to fit the spindle at each end of the hole, substantially the same as when the disk is used; but as a matter of economy, I prefer the use of the disk.

What I claim is:—

1. A spindle, a whirl-base having its shank or upper portion counterbored and a chamber in its lower end, and a disk and whirl arranged in said chamber, said whirl-base adapted to be securely attached to the spindle by the upper end of its shank and the disk. 70

2. A spindle, a whirl-base having its shank counterbored and a disk at the lower 80 end of said counterbore, said whirl-base securely attached to the spindle by the upper end of its shank and the said disk, combined with a bobbin-holder, securely attached to the spindle above the whirl-base and sleeves 85 the counterbored shank of the whirl-base and adapted to engage the lower end of a bobbin.

3. A spindle, a whirl-base constructed with two spindle-engaging elements to fit the 90 spindle at two points, one of which is above and the other below the bottom rest for the bobbin and out of contact with the spindle between said points.

In testimony whereof I have hereunto set 95 my hand this 28th day of December, A. D. 1909.

CHARLES H. CHAPMAN.
